COLLAPSIBLE TUBE DISPENSER

Edward Thomas Hickey, 243 W. Foxdale Drive,

Milwaukee, Wis.

Filed July 26, 1961, Ser. No. 126,926

3 Claims. (Cl. 222—100)

This invention relates to a device for dispensing the contents of a collapsible tube of viscous material such as tooth paste or the like, and more particularly to a manually operable roller for expressing the tube contents in cooperation with a resilient snap-on member which may also afford a stand for the tube.

Heretofore, various tube collapsing devices have been available which have included rollers and compression means, but such devices have in general been unwieldy and cumbersome or have required attachment to a wall surface or the like. The present invention affords an extremely simple and compact construction which does not need to be connected to a support surface and in fact provides a means of supporting a tube of material such as tooth paste or the like in a display position and which extrudes the contents of the tube with minimal effort. Thus the device includes a spool which is slotted axially and radially, with the inner portion of the slot being enlarged for the reception of the end of the collapsible tube. The spool may be of a sufficient length to accommodate the tubes of a variety of widths and after insertion of a closed end of the tube in the slot, a resilient member is slipped over the spool so that a segmental cylindrical portion thereof closely engages the spool for a major portion of the spool periphery to effect retention thereon. The free end of the resilient member is formed in an S-loop, in a suitable embodiment of the invention, so that hand pressure may be applied thereagainst to collapse the lower end of the tube. As the contents of the tube are dispensed, the spool is turned by means of knurled ends thereon to engage a fresh portion of the lower end of the tube, and this procedure may be continued until the entire contents of the tube have been dispensed.

Accordingly, it is an object of the present invention to provide a collapsible tube dispenser that will support the tube in a vertical or standing position for storage and ready access, or so that the printed matter thereon may be displayed for a long period of time for advertising purposes.

Another object of the invention is to provide a collapsible tube dispenser that can be held and operated with one hand and which has a knurled knob or hand grip on opposite ends of the spool or roller, for positioning the tube to receive the pressure applied by hand to a resilient member or spring plate so as to dispense the contents of the tube.

Another object of the invention is to provide a collapsible tube dispenser as described which will accommodate a variety of tube sizes without adjustment of the device.

Another object of the invention is to provide a collapsible tube dispenser which affords removal of the collapsed tube without necessitating dismantling of the device, since the tube may simply be slid axially out of the spool or roller.

Another object of the invention is to provide a collapsible tube dispenser having only two parts.

Another object of the invention is to provide a collapsible tube dispenser that is portable with the tube secured in place therein.

A further object of the invention is to provide a collapsible tube dispenser that affords a closely controlled extrusion of the contents of the tube.

Yet another object of the invention is to provide a

2

collapsible tube dispenser as described which may be used with tubes containing a wide variety of types of material.

Other objects and advantages of the invention will become apparent as the description proceeds in accordance with the drawings in which

FIGURE 1 is a perspective view of the device of the invention in operative relation to a tube from which material is to be dispensed;

FIGURE 2 is a front elevational view of the device of the invention in supporting relation to a collapsible tube;

FIGURE 3 is a side elevational view, partly in vertical section as taken along the lines III—III of FIGURE 2; and

FIGURE 4 is a vertical sectional view, partly broken away, of another embodiment of the device of the invention.

Referring now to the drawings, a dispensing device 10 is shown in FIGURES 1 through 3 in operative relation to a collapsible tube 11 containing a viscous material 12 such as tooth paste, although any of a wide variety of materials of paste-like or semifluid consistency may be dispensed by means of the invention. The tube 11 may be of any conventional type, such as a tube formed of flexible metal, plastic or other sheet material. Thus the tube may have a cap 13 threadedly or otherwise releasably secured to a nozzle 14 for ready removal as desired to place the tube in condition for dispensing the material 12. And, as also understood by those skilled in the art, the tube may have a bottom seam 15 which may constitute a fold suitably sealed to close off the free end of the tube and which in general will have a thickness somewhat greater than the thickness of the tube in its collapsed or empty condition.

The device 10 constitutes a dispenser for the collapsible tube 11, or for any of a variety of tubes of varying dimensions, and includes a spool or roller 16 which may be made of any suitable material, exemplary of which are plastics of cast or molded type, wood, metal, preferably of a light weight characteristic, or other materials. In accordance with the invention, one or both ends of the spool 16 have secured thereto, either integrally or by suitable connecting means, a knurled hand grip 17.

The knurled hand grips 17 are preferably of generally circular cross sectional configuration and are of a diameter somewhat greater than the diameter of the spool 16. However, it will be appreciated that variations in this particular construction may be encompassed within the scope of the invention, and, for example, the hand grips may be reduced relative to the diameter of the spool 16, and other means for manually applying torque to the spool 16 may be utilized within the scope of the invention, as herein-after set forth. The spool 16 has formed therein a preferably radially aligned slot 18 of a width sufficient to accommodate the marginal end portions of the tube, and preferably approaching the width of the tube in its collapsed condition. The slot 18 may extend inwardly into the spool 16 for a distance which is preferably less than the radius of the spool, and the innermost portion of the slot is enlarged as shown at 19 to accommodate the seam or closure 15 on the end of a tube such as the tube 11.

In order to permit assembly and disassembly of the tube with respect to the spool 16 without complicated manipulation and separation of the parts of the device 10, the slot 18 preferably extends axially for the full axial dimension of the spool 16 and also through one or both of the hand grips 17. Thereby, the enlarged portion 15 at the free end of the tube may be inserted in the enlarged slot portion 19 from one side or the other as desired of the roller structure, and thereupon slidably moved to a center position with respect to the spool 16, as shown in FIGURE 2. A further advantage of this

construction resides in the fact that the spool 16 is of a sufficient axial dimension to accommodate tubes of a wide range of dimension, so that there is no need for manufacturing a separate size of the device of the invention for each size of tube.

In accordance with the invention, a resilient member 20 is provided which serves the dual function of cooperating with the spool 16 in extruding materials from the tube 11, and of supporting the tube in a vertical position so that little space is required for storage, in contrast to the space taken up by tubes which are placed horizontally. An important advantage is also found in the fact the tube is thereby positioned for effective display, so that the labeling and other indicia thereon may be readily observed. To this end, the resilient member 20 includes a segmental cylindrical portion 21 which is preferably of a diameter approximating the diameter of the spool 16 or somewhat reduced relative thereto, and a free end portion 22 which, in the embodiment of FIGURES 1 through 3, is formed in an S-loop.

It will thus be seen that the segmental cylindrical portion 21 affords a snap-on connection for the resilient member 20, and circumscribes an arc which is substantially greater than 180°, to afford a bearing for secure rotary engagement with the said spool. The resilient member 20 may be constructed of spring metal, or suitable material, and the S-shaped loop 22 includes a flat or slightly curved applicator or cam portion 23 which may extend substantially tangentially from the segmental cylindrical portion 21 in a planar or slightly convexly bowed configuration. The relatively planar or flat portion 23 forms an applicator or cam surface, as hereinafter described, and preferably extends outwardly from the segmental cylindrical portion 21 a substantial distance such that the reversely turned portion 24 of the S-shaped loop 22 is disposed in protruding relation to the tube in the assembled condition of the device. The S-shaped loop 22 also defines a return reach 25 extending generally in the direction of the segmental cylindrical portion 21 and in spaced relation to the planar portion 23, and a preferably segmental spherical portion 26 which is reversely turned with respect to the turn 24. As best seen in FIGURE 3, the terminal area of the recess-providing segmental cylindrical portion 21 at one side of the entrance into the recess and the portion 23 at the opposite side of the recess afford not only generally convergent lead-in surfaces facilitating snap-on movement of the spool 16 into the recess by spreading apart of the portions 21 and 23 by resilient deflection, but also afford generally confronting surfaces between which the inserted portion of the tube 11 is engaged to facilitate squeezing the tube to force the tube contents from the nozzle 14 by moving the portion 23 toward the opposing surface, generally as depicted in FIGURE 1.

It will thus be seen that the S-shaped loop provides a means of exerting pressure on the tube such that the contents at the bottom are thoroughly expressed and a gradually widening opening between the spool 16 and the surface 23 is afforded for the materials thus squeezed from the bottom.

The end loop portion 26 is disposed in register with the loop portion 21 and thereby affords a stable base for the tube such as to maintain it in a substantially vertical position as shown. It will, of course, be appreciated that variations of the particular construction of the loop portion 26 will be encompassed within the scope of the invention.

The resilient member 20 is easily formed since it is of a sheet metal or other spring metal construction and can be readily bent to the desired configuration by conventional techniques requiring minimal outlay for equipment and labor.

Referring now to FIGURE 4, another embodiment of the invention is seen wherein the roller construction is substantially identical to the construction shown in FIGURES

1 through 3 and the resilient member 20a is formed of a plastic material rather than a resilient metal. In this construction, the segmental cylindrical portion 21a and the registered segmental cylindrical portion 26a are substantially identical, in a preferred form, to that shown in the preceding embodiment except that the outwardly extending free end portion may be made as a solid lever construction 27. This formation makes casting or molding of the resilient member easy to accomplish, although it will be understood that a sheet form construction may be utilized also within the scope of the invention. A further advantage of the solid construction of the portion 27 resides in the fact that a secure and stable relation between the segmental portions 21a and 26a is thereby afforded.

Thus it will be seen that a snap-on assembly is provided which requires only two parts, and in operation the tube 11 may be slid into the spool 16 as described and the resilient member 20, or 20a, thereupon snapped into position where it may support the tube in vertical alignment so that it may be picked up readily for use or utilized in a display for advertising purposes. Once the cap 13 of the tube 11 has been removed, the material, such as tooth paste or the like, may be dispensed by simply pressing the extension portion of the resilient member 20 as described and as indicated in FIGURE 1, it being understood that this may be accomplished in a variety of ways as is most convenient to the user. When the tube has become sufficiently emptied by the squeezing operation, a further supply of material may be expressed by rotating the spool 16 by means of the knurled hand grips 17, and it will therefore be appreciated that the dispensing of the material may be accomplished with one or either hand as desired. And because of the slot construction in the spool, the collapsed tube may be removed without dismantling the device. The tube dispenser of the invention may be transported with the tube in place and also affords a highly convenient and desirable assembly with the tube for sales purposes.

Accordingly, there has been provided a tube dispenser of unusual simplicity and ease of operation, and which may be used with a wide variety of sizes of tubes as well as with tubes containing many types of material. There is, therefore, a broad range of application for the dispenser in addition to the particular use referred to.

Although I have herein set forth and described my invention with respect to certain specific principles and details thereof, it will be understood by those skilled in the art that these may be varied without departing from the spirit and scope of the invention as set forth in the hereunto appended claims.

I claim as my invention:

1. A dispenser for supporting in generally upright relation to a horizontal surface a collapsible filled tube having a closed lower end and a nozzle at the opposite upper end from which material contents are to be discharged by squeezing pressure applied to the tube,

said dispenser comprising a spool having manipulating means on at least one end thereof and means intermediate its ends for engaging the closed end of the tube, and a resiliently flexible member supporting the spool rotatably and including:

a spool bearing portion affording with the spool therein a supporting base structure engageable with said horizontal surface,

said bearing portion having upper opposed generally convergently related end portions defining therebetween an upward entry opening through which the closed end of the tube is received,

said end portions being spaced apart substantially less than the normal thickness of the filled tube and providing confronting surfaces which engage the respective opposite sides of the tube, one of said end portions projecting a substantial distance beyond the other of said end portions in

supporting relation to its side of the tube and having a supporting base part projecting downwardly opposite to its tube-engaging surface for engaging the horizontal surface spaced from the bearing portion so as to provide with said base structure a stable upright base support for the dispenser and tube,
 5 said one end portion being resiliently manually flexibly movable toward the confronting tube-engaging surface of the other end portion to squeeze the engaged walls of the tube toward one another and thereby force material from the tube through the nozzle,
 said spool being rotatable for taking up the closed end portion of the tube as the material is dis-
 placed therefrom.

2. A dispenser as defined in claim 1, wherein the upper free end portion of said one end portion of the member

above said supporting base part and above said bearing portion comprises a solid lever construction.

3. A dispenser as defined in claim 1, wherein said one end portion of the member extends diagonally upwardly substantially tangentially to said bearing portion and said upward entry opening is located over the tangential meeting of the bearing portion and said one end portion and eccentric to the spool axis.
